CLAIM

The ornamental design for an insulating housing for gas device, as shown and described.

DESCRIPTION

This invention was made with government support under SBIR Phase II Award No. 1632439 awarded by the National Science Foundation. The government has certain rights in the invention.

FIG. 1 is a front, top, right side perspective view of the insulating housing for gas device;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 shows a front, top, right side perspective view thereof, with environmental features shown.

The broken lines in the figures show portions of the insulating housing for gas device that form no part of the claimed design. The additional broken lines in FIG. 8 depict environmental subject matter that forms no part of the claimed design.
